CLOSURE FOR CONTAINERS

Norman E. H. Deletzke, Chicago, Ill., assignor to
Cherry-Burrell Corporation, Wilmington, Del.,
a corporation

Application January 25, 1937, Serial No. 122,134

8 Claims. (Cl. 215—38)

This invention relates to receptacles and closures therefor. It is especially applicable to receptacles such as glass bottles used in the bottling of milk, and more particularly applies to receptacle closures of the type in which a thin pliable hood cap is molded or crimped over the mouth of the receptacle to coactingly engage parts thereof, which will seal the cap over the mouth of the receptacle and hold it in place until intentionally removed therefrom.

It is common knowledge in the art of container closures employing a thin, pliable closure cap, such as aluminum foil, in which a depending flange is formed about the container mouth, that the preferred sealing contact is formed at the line of shouldering engagement between the detents in the molded or crimped flange and the complementary engaging provisions on the outer periphery of the container neck. It is also common knowledge that the weakest point in the sealing contact is at the point of interruption or end of the said line of shouldering engagement. To enable the removal of closure caps from the container mouth, following a relative rotation of the cap upon the container, discontinuous or interrupted cap engaging provisions are commonly employed to obliterate the engaging detents formed in the cap's depending flange in the molding or capping action. The ends of the discontinuous engaging provisions, as well as the said interruptions in the engaging provisions, serve as fulcrum to obliterate the retaining detents and the sealing contact when the closure cap is relatively rotated upon the container mouth, and constitutes points of defective sealing contact, which are easily broken down.

It is, therefore, the object of my invention to provide a closure for containers, milk bottles in particular, which can easily and quickly be applied and removed, which, when applied, is retained in position against accidental removal and forms an uninterrupted, continuous and uniform sealing contact with a complementary, annular, cap engaging provision on the outer periphery of the bottle neck.

Another object is to provide a closure for containers in which, after removal, the pliable, or metal foil hood, will have substantially retained its original shape, thus insuring a close fit of the cap upon the container mouth when subsequently reused and yet showing that the cap has been removed following its original application.

A further object of the invention is to provide a closure for a container, milk bottles in particular, which when applied protects the mouth and

pouring lip of the bottle against contamination, and which upon relative rotation of the cap upon the bottle simultaneously breaks all the combined sealing and retaining detents.

My invention is adaptable for and may be embodied in container closures of various types, such as closures for milk bottles, beer and other beverage bottles, fruit and condiment jars, as well as metal containers, such as are used in the paint and oil industries, etc.; however, I have selected a milk bottle as my preferred form of illustration.

The foregoing objects and others ancillary thereto, I prefer to accomplish as illustrated in the preferred embodiment of my invention in a milk bottle neck and bottle closure which I provide with a plurality of improved and important features.

The invention itself, both as to organization and method of operation, together with additional objects and advantages thereof, will best be understood from the following description of the specific embodiment which when read in connection with the accompanying drawing in which—

Figure 1 is an elevation on an exaggerated scale partially in section of the upper portion of a milk bottle showing one construction according to my invention.

Figure 2 is a view similar to Figure 1, but at a 90° angle to the plane of Figure 1.

Figure 3 is an elevation of a partially preformed closure cap of the type contemplated by this invention.

Figure 4 is a view of the upper portion of a milk bottle similar to Figure 1 having the cap applied thereto.

Figure 5 is a transverse sectional plan view on line A—A of Figure 1.

Corresponding parts in all the figures are denoted by the same letters of reference.

Referring to the figures by characters of reference, the container neck 1 is provided adjacent its pouring lip 2 with a circumferentially extending, ununiformly inclined, continuous, annular ridge 3 of wavy contour, with a crest 4 and a trough 5 and a beveled sealing surface 6 on its lower side. Projections 7 on the outer surface of the container neck 1 and adjacent to the upper surface of the wash ring 8, but not contacting the ridge 3, are provided to expand the lower portions of the crimpings 11 in the depending cap flange 10 of the hood cap, which is provided with a lid 9 to contact the pouring lip 2 of the container neck. The projections 7 are

positioned beneath the crest 4 of the wavy ridge 3 and extend from a point lower than the edge 12 of the cap skirt 10 upwards to a point less remote from the pouring lip 2 than the trough 5 of the wavy ridge 3. The depending cap skirt 10 completely covers the wavy ridge 3. The projection 7 extends radially from the neck of the container in an extent equal to or greater than the radial extent of the wavy ridge 3.

- 10 The preferred method of removing a cap of the type contemplated by this invention from a container such as a milk bottle, is to grip the container in one hand, press the palm of the other hand against the lid of the closure cap, thereby holding it in close contact with the pouring lip 2 of the container, and then rotating the cap relative to the container. By such rotation of the cap, the detents in the cap skirt forming a complementary rib in sealing contact with the beveled surface of the wavy ridge in the container neck, will be forced into engagement with uncomplementary portions of the beveled surface. The ununiformly and radially inclined wall of the ridge will have a wedging action on the detents in the cap skirt, as the cap is rotated relative to the container. After a partial rotation of the cap upon the container, the sealing contact will be broken and the detents in the cap skirt pushed out of shouldering engagement with 20 the groove in the container neck. The cap may then be removed from the container and subsequently reused as a closure to prevent contamination of the container mouth. The unique way of removing the crimpings embossed in the cap skirt in the capping action, intermediate the upper and lower portions of the depending skirt, will enable the detection of any tampering with the container closure after its original application—yet will not so flare the remaining portions 30 of the cap skirt to prevent partial sealing upon subsequent reuse of the cap.

The cap to be used with the container may be constructed of thin, pliable material, such as metal foil, i. e., aluminum foil or other pliable 40 shape-retaining materials, which can be molded or formed over the neck of the container. The preferred form constitutes a hood cap provided with a lid 9 and a depending cap flange 10 as shown in Figure 3. The inner diameter of the 45 depending cap flange 10 is slightly larger than the external diameter of the container mouth over which it is applied. The advantages of the invention may be fully attained by constructing the caps of material of sufficient pliability and thinness that it may conform readily to the cap engaging provisions in the container mouth, and that without tools but by the unique coaction of the cap engaging and sealing means, it may be readily rotated on the container by hand to disengage it from the retaining shoulder. To apply the cap to the container, it is necessary after placing the cap on the container mouth, to apply lateral inward pressure to its depending skirt by means of a pneumatic die or similar instrument to cause the skirt to conform to the outer surface of the container and to emboss a rib 11 as shown in Figure 4 into the depending skirt, which will be complementary to and shoulderingly engage the ridge 3 in a continuous uninterrupted sealing contact. Thus the cap is provided with detents which engage the cap engaging shoulder 6 and bosses 1, holding the cap in its applied position as intended, thus sealing the top of the container and protecting the mouth of it against contamination.

The bottle is preferably provided below and adjacent the cap engaging shoulder with a rounded annular bead or engagement 8. This bead aids in strengthening the bottle, protects the hood cap applied to the bottle and constitutes a convenient grip for the lifting or carrying of the bottle. The bead 8 is also a satisfactory holding element for engagement with holding means in the bottle washing and filling apparatus.

My invention, therefore, provides a closure for containers, which can be easily and quickly removed and which when applied to the container is retained in position against accidental removal, and which forms an uninterrupted continuous sealing contact, as well as protects the mouth of the container against contamination. As pointed out, the unique way of expanding the crimpings in the depending flange of the cap skirt, as well as forming a sealing contact, will permit of the easy removal of the cap from the container when the cap is rotated relative to the container mouth, as well as its subsequent reuse.

Although I have shown and described certain specific embodiments of my invention, I am fully aware of the many possible modifications thereof. My invention is, therefore, not to be restricted except insofar as necessitated by the prior art and the spirit of the applied claims.

As my invention, I, therefore, claim:

1. The combination of a receptacle having a continuous, annular, cap engaging rib of undulating contour formed on the outer periphery of the neck thereof adjacent the orifice of said receptacle, and a skirted closure cap of pliable, shape retaining material applied to the receptacle mouth and molded in position thereon, said cap skirt being provided with a rib formed in said capping operation complementary to said rib of undulating contour on the outer periphery of the 40 container neck, whereby said cap may be loosened for removal and the said complementary rib in its skirt simultaneously obliterated by turning the cap angularly upon the container.

2. In combination with a container having 45 formed externally on the neck thereof adjacent its orifice a continuous uninterrupted cap engaging rib of undulating contour relative to the mouth of the container, a skirted closure cap of pliable material placed on the container mouth with a complementary uninterrupted rib pressed into its depending skirt in the capping operation and shaped into conformity with the said cap engaging rib to yieldably maintain the cap in sealing contact therewith, whereby the closure 50 cap may be loosened for removal, and the complementary rib in the depending flange simultaneously obliterated by turning the cap angularly on the container mouth.

3. A closure combination comprising a container having an uninterrupted annular cap engaging rib of undulating contour relative to the container mouth formed on the outer periphery of the neck of said container, one or more projections on the outer periphery of said container neck, said projections extending radially a distance equal to or greater than the radial extent of said rib and extending axially relative to the container from a point more remote from the container mouth than the trough of said rib of 60 undulating contour to a point less remote from the mouth than the trough of said rib of undulating contour, a skirted closure cap of pliable material applied to the mouth of the container and having the skirt portion molded in position 65

about said rib, with the lower edge of said cap traversing said projections to coact with said cap engaging rib in sealing contact to maintain said cap in place against accidental displacement by 5 the complementary rib and complementary projections so formed in the skirt, whereby said cap may be loosened for removal and the complementary rib and projections simultaneously obliterated by turning the cap angularly upon the 10 container.

4. A container provided on the outer periphery of its neck adjacent its mouth with a cap engaging rib of undulating contour axially and radially of the container neck, a skirted container cap of pliable material placed over the container mouth and there molded in secure position to engage said rib in a sealing contact by a continuous complementary rib formed in said cap skirt by the molding operation, said rib constituting a double acting wedge to disengage said complementary rib upon rotation of the cap 20 upon the container mouth.

5. A bottle having a neck provided adjacent its mouth with an uninterrupted, external, circumferential rib of undulating contour, bosses on the outer periphery of said bottle neck contiguous therewith and positioned remotely from said rib, a flanged closure cap of thin pliable material molded in place over the bottle mouth 30 with an embossed uninterrupted rib in said cap flange complementary to said rib of undulating contour, said bosses extending radially a distance equal to or greater than the radial extent of said first mentioned rib and extending axially above

the trough of said rib of undulating contour and below the lower edge of the flange of said closure cap, whereby upon relative rotation of the cap upon the container the said complementary rib will be obliterated and the lower portion of the 5 cap flange expanded.

6. The combination in a bottle having a neck and a pouring outlet, of a continuous annular pouring and cap engaging flange of undulating contour on the outer periphery of said neck immediately below said pouring outlet.

7. The combination in a bottle having a neck and a pouring outlet, of a continuous annular pouring and cap engaging rib of undulating contour on the outer periphery of said neck immediately below said pouring outlet, said pouring and cap engaging rib having an upwardly and inwardly inclined upper face and an inwardly and downwardly inclined lower face constructed and arranged to deflect the liquid from said neck 20 portion below said rib during the pouring operation.

8. A container provided on the outer periphery of its neck adjacent its mouth with a cap engaging rib of undulating contour axially of the container neck, a skirted container cap of pliable material placed over the container mouth and there molded in secure position to engage said rib in sealing contact by a continuous complementary rib formed in said cap skirt by the molding operation, said rib constituting a wedge to 30 disengage said complementary rib upon the rotation of the cap upon the container mouth.
